UNITED STATES PATENT OFFICE.

EDWIN H. FORD, OF NEW BEDFORD, MASSACHUSETTS.

HAND-THREADING ANTISUCTION-SHUTTLE.

1,071,039.

Specification of Letters Patent. Patented Aug. 26, 1913.

Application filed May 15, 1911. Serial No. 627,147.

To all whom it may concern:

Be it known that I, EDWIN H. FORD, a citizen of the United States, residing at New Bedford, in the county of Bristol and State 5 of Massachusetts, have invented certain new and useful Improvements in Hand-Thread- 10 ing Antisuction-Shuttles, of which the following is a specification.

This invention relates to new and useful 15 improvements in shuttles, and relates more particularly to an anti-suction shuttle and a threading device by means of which the shuttle may be threaded by hand instead of by suction.

With the foregoing objects in view, the 20 invention consists in the novel features of construction, combination and arrangement of parts illustrated in the drawings and more particularly pointed out in the ap-

25 pended claims.

In the accompanying drawings:—Figure 1 is a top plan view of the threading end of a shuttle embodying my improvements. Fig. 2 is a bottom plan view thereof. Fig. 3 is a side elevation, illustrating one step in the process of threading the shuttle. Fig. 4 is a top plan view of a modification of the threading end of a shuttle. Fig. 5 is a longitudinal section taken on the line 5—5 of Fig. 4. Fig. 6 is an elevation of a threading device used in threading the shuttle, and Fig. 7 is a sectional view taken on the line 7—7 of Fig. 6.

Referring to the drawings for a more 30 particular description of the invention, 1 indicates the shuttle provided with the usual shuttle eye 2. In carrying out the present invention the bottom of the shuttle is also provided with the eye 3 which is directly in line and concentric with the eye 2. The eye 3 has formed in its wall the niche or slit 4 extending in a direction toward the shuttle tip 5.

The numeral 6 indicates the side eye which 35 extends laterally through one side of the shuttle and communicates with the eye 2.

7 indicates the threading device comprising the handle 8, the wire shank 9 provided at its outer end with the inwardly bent hook 50 10, and the resilient tip 11 of cork at the inner end of the handle. The top of the handle is flattened as at 12, on the plane of the hook 10.

In threading the shuttle, the shank 9 of

the threading device is passed through the 55 eyes 3 and 2 in the manner illustrated in Fig. 3 with the tip of the handle fitting in the eye 3, whereby the device is held in the shuttle with the flattened side 12 of the handle 8 upward or toward the nearest tip 60 of the shuttle, thus giving the operator, by sense of feeling, the proper position of the hooked end of the shank. The operator then takes up the shuttle for refilling, leaving both hands free for the raising of the spin- 65 dle, the removal therefrom of waste and tube, and the replacing of a new filling. The loose filling end is then passed over the hooked end of the shank, and the device drawn backward until free of the shuttle 70 followed by a slight upward movement to engage the filling in the slit 4 of the eye 3. The hook is then inserted in the side eye 6 to engage the filling inside the shuttle which is then drawn through, completing the oper- 75 ation.

While a shuttle constructed as shown in Figs. 1 to 3, cannot ordinarily be threaded by suction, yet this could be accomplished by placing the finger over the eye 3, and 80 therefore to obviate this possibility and make the shuttle an absolutely anti-suction one, a downwardly inclined passage 13 is formed in the slanting wall 14 of the filling runway, which acts as a vent for the shuttle 85 eye. It is not possible to cover the passage 13 with the finger tip owing to the narrowness of the runway at the point pierced by said passage.

From the foregoing description taken in 90 connection with the drawings it is thought that the construction and advantages of this invention will be readily understood without requiring a more extended explanation.

Having described my invention what I 95 claim as new and desire to secure by Letters Patent, is:

1. An anti-suction shuttle of the class described provided with a shuttle eye communicating with the shuttle throat and in its bottom with an outwardly flared eye communicating with the shuttle eye and provided in its wall with a slit extending in a direction toward the shuttle tip, said shuttle also having a side eye communicating with the 105 shuttle eye and a downwardly inclined passage extending through the wall of the filling runway to the shuttle eye and acting as

a vent to avoid possibility of threading the shuttle by suction.

2. An anti-suction shuttle provided with an eye communicating with the shuttle 5 throat, an exit side eye in communication with said eye and an inclined passage extending from the throat to one of said eyes.

In testimony whereof I affix my signature in presence of two witnesses.

EDWIN H. FORD.
